DOOR LOCK AND LATCH

Ernest L. Teich, New Britain, Conn., assignor to
The American Hardware Corporation, New
Britain, Conn., a corporation of Connecticut

Application June 22, 1951, Serial No. 233,508

10 Claims. (Cl. 70—146)

1

The present invention relates to door locks and latches of the type that are provided with dead locking means.

One of the objects of the invention is to provide a lock or latch of the character indicated which is of simple and strong construction, easily and quickly assembled and applied to a door, and reliable and convenient in use.

Another of the objects of the invention is to provide novel and improved dead locking means for locks and latches.

The invention is illustrated, by way of example, in the accompanying drawings, in which:

Figure 1 is a side view of a portion of a door having my improved lock in its preferred form applied thereto;

Fig. 2 is an edge view of the same;

Fig. 3 is a sectional elevation on an enlarged scale taken substantially on the line 3—3 of Fig. 2;

Fig. 4 is a sectional elevation taken substantially on the line 4—4 of Fig. 3;

Figs. 5 and 6 are views similar to Fig. 3 with parts shown in a different position, Fig. 6 also illustrating a pin which may be employed for releasing the dead locking means from the outside of the door;

Figs. 7 and 8 are sectional views, partly in elevation, respectively taken on the lines 7—7 and 8—8 of Fig. 6;

Fig. 9 is a sectional view, partly in elevation, taken on the line 9—9 of Figs. 6 and 11;

Fig. 10 is a sectional view taken on the line 10—10 of Fig. 11;

Fig. 11 is a sectional view, partly in elevation, taken on the line 11—11 of Fig. 6;

Fig. 12 is a sectional view, partly in elevation, taken on the line 12—12 of Fig. 11;

Fig. 13 is a detail side elevation of a rod for operating the dead-locking means;

Fig. 14 is a sectional elevation corresponding substantially to Fig. 5, of a modified form with the escutcheon plates of the lock removed, certain parts being shown by dotted lines in locked position;

Fig. 15 is a sectional plan view taken substantially on the line 15—15 of Fig. 14;

Fig. 16 is a transverse sectional view taken substantially on the line 16—16 of Fig. 14; and

Fig. 17 is a detail sectional view taken on the line 17—17 of Fig. 15.

The present application is a continuation in part of my pending application Ser. No. 598,542, filed June 9, 1945, now abandoned.

As shown, the lock or latch is adapted to be mounted in a U-shaped slot 2 in a door 4. The

housing of the latch comprises an outer escutcheon plate 6 and an inner escutcheon plate 7 which are adapted to be secured to the door by means of screws 8 in the usual manner. Inside of the escutcheon plates is a frame comprising horizontal plate members 10 which are connected by an end plate 12, a central plate or partition 14, and a hollow spindle supporting bushing 16. The bushing 16 has projecting ends 18 which extend outwardly through bosses 20 on the escutcheon plates 6 and 7. A removable sheet metal cover 21 extends over the top and bottom and rear side of the frame.

The latch is provided with an outer knob 22 and an inner knob 24 which are respectively provided with spindles 26 and 28. These knob spindles extend into opposite ends of the bushing 16 and are provided with shoulders 30 which are arranged adjacent the ends of the bushing. The knob spindles are held from axial movement by means of a U-shaped keeper-plate 32 which is secured to the bushing 16 by means of a screw 34, the ends of the keeper being received in annular grooves 36 in the spindles.

The latch is provided with a latch bolt 38 which is pivoted on a pin 40 in the end plate 12 of the lock housing, the latch bolt working in an opening in said end plate. The latch bolt is pivotally connected by a pivot pin or screw 42 with the outer end of the rod portion of a bolt retractor 44, the retractor being pressed in a direction to project the latch bolt by means of a spring 46 coiled about the rod portion of the retractor and interposed between the latch bolt and the partition plate 14 of the frame or housing. The inner portion of the retractor is in the form of a yoke, the inner ends of which are provided with laterally extending lugs 48.

The retractor lugs 48 are adapted to be acted upon by either of the arms of two roll-backs 50 and 52 to retract the latch bolt. The roll-back 50 is connected with the spindle 26 of the outer knob 22, and the roll-back 52 is connected with the spindle 28 of the inner knob 24 whereby upon turning either knob in either direction the roll-back connected therewith acts through the retractor to retract the latch bolt against the tension of the spring 46.

The inner roll-back 52 is provided with a hub portion mounted in the inner end of the inner knob spindle 28, and is provided with oppositely projecting arms which extend through opposed slots 54 in the inner end of said spindle and through clearance slots 56 in the housing bushing 16 with the ends of the roll-back arms arranged

to respectively engage the retractor lugs 48 (Figs. 10 and 11). This roll-back 52 is held from axial movement by being positioned between the abutting end of the outer knob spindle 26 and a shoulder 51 in the inner knob spindle 28 (Fig. 12).

The outer roll-back 50 has its hub mounted to slide in the inner end portion of the spindle of the outer knob spindle 26 with the projecting arms thereof extending through elongated slots 59 in the inner end portion of said spindle.

In accordance with the invention, the latch is further provided with a dead locking rod 58 which extends axially through the knob spindles, and through central apertures in the roll-backs 50 and 52. This rod 58 is mounted to slide freely through the roll-back 52, but is held from axial movement with relation to the outer roll-back 50 by means of projections 60 on the rod adjacent one side of the roll-back, and a suitable clip 62 detachably secured about the rod having its inner end arranged adjacent the outer side of the roll-back 50. The inner end of the rod 58 is in the form of a push button 64 which extends through a guiding aperture in the outer wall of the inner knob 24.

The outer end of the dead-locking rod 58 is reduced in diameter and extends into a guiding sleeve 66, the outer end of which embraces an inwardly directed flange surrounding an aperture 68 in the outer side of the outer knob. A spring 70 is coiled about the sleeve 66 and is interposed between the flanged outer end of the sleeve and a collar 72 on the reduced portion of the rod 58, the spring thus tending to press the rod in a direction to project the push button 64.

With the dead-locking rod 58 in its released position as shown in Figs. 3 and 5, the outer roll-back 50 is arranged adjacent the roll-back 52, and upon turning either knob in either direction its roll-back acts through the retractor to retract the latch bolt.

Upon shifting the rod 58 by depressing the push button 64, the outer roll-back 50 is shifted outwardly to position the arms thereof in slots 74 in the spindle bushing 16 of the housing (Fig. 11), thus dead-locking the outer knob. The dead-locking rod 58 and the roll-back 50 are held in this position by engagement of the arms of the roll-back with rounded projections 76 on the retractor lugs 48, the retractor spring 46 permitting the arms of the roll-back 50 to snap over the projections 76 when the push button is depressed.

When the door is closed and the outer knob is thus dead-locked, upon turning the inner knob to retract the latch bolt and open the door, the retracting movement of the bolt-retractor releases the projections 76 from the roll-back 50, whereupon the spring 70 acts to shift the rod 58 into its released position, thus moving the roll-back 50 out of the dead-locking slots 74 and releasing the outer knob.

The dead-locking means may also be released by inserting a pin or other suitable implement 78 through the aperture 68 in the outer knob and forcing the rod inwardly to cause the arms of the outer roll-back 50 to ride over the projections 76, and thus permitting the spring 70 to move the rod into released position.

In case the push-button 64 is accidentally depressed so as to dead-lock the outer knob, the depression of the latch upon closing the door effects release of the outer roll-back 50 and thus release of the dead-locking means.

The modified form shown in Figs. 14, 15 and 16 is provided with outer and inner knobs 22' and

24', knob spindles 26' and 28' that extend into opposite ends of a bushing 16', a bolt retractor 44' having laterally extending lugs 48', roll-backs 50' and 52' respectively connected with the outer and inner knob spindles, a dead locking rod 58', and rounded projections 76' on said retractor lugs 48'. Except as hereinafter described these parts may be the same in construction and mode of operation as the corresponding parts of the lock above described.

The dead locking rod 58' of this form, instead of being pressed inwardly by means of a spring 70 at the outer end of the rod, has a spring 80 coiled about the rod and interposed between a collar 82 on the rod and a shoulder in the inner knob spindle 28'.

The outer end of the rod 58' has secured thereon a cam sleeve 84, the outer end of which has a transverse concave V-shaped cam surface 86. In alignment with this cam surface, is a convex V-shaped cam surface 88 formed on the end of a cam sleeve 90 which is secured on the inner end of a key-operable plug 92 of a cylinder lock 94. This lock 94 is mounted in the outer knob 22'. The outer end of the cylinder is mounted in a groove in the rim of a key opening in the outer wall of the knob, and the inner end of the cylinder is mounted in the outer end of the outer knob spindle 26', the margin of the inner end of the cylinder abutting a flange 96 on the inner end of the spindle.

The projections 76' may be formed on the ends of a spring-pressed plunger 98, instead of being rigid with the bolt retractor. Also, instead of the outer roll-back being held from outward movement by the clip 62, a sleeve 100 is interposed between the roll-back and the cam sleeve 84.

With this construction, upon depressing the push-button on the inner end of the dead-locking rod to lock the door, the cam surface 86 in the sleeve 84 is shifted into engagement with the cam surface 88 on the cam sleeve 90.

In case of emergency if it is desired to unlock the door from the outside, upon turning the cylinder plug by means of a key, the engaging cam surfaces 86 and 88 serve to shift the dead-locking rod 58' inwardly, thus releasing the outer knob spindle to permit the knob to be turned to retract the latch bolt. Upon turning the key plug to its initial key removal position, the dead-locking rod may be again shifted by its push-button to lock the outer knob.

In order to prevent turning of the dead-locking rod 58' during shifting thereof by means of the key plug, a washer 101 is located in a recess in the inner knob spindle 28' adjacent the inner roll-back 52'. This washer is provided with laterally projecting lugs 102 that are received in openings in the spindle, so as to hold the washer from turning relatively to the spindle. The washer is provided with a square aperture through which the dead-locking rod extends, so as to prevent turning of the rod but permitting axial movement thereof. This construction does not prevent turning the inside knob when button is depressed and outside knob is locked. When the button is depressed to lock the outside knob, turning of the inside knob moves the retractor and with it the spring pressed plunger 76', thus permitting the rod and outer roll-back to be shifted inwardly by its spring 80 to release the outside knob, and the inside knob to be turned to unlatch the door.

As will be evident to those skilled in the art my invention permits various modifications with-

out departing from the spirit thereof or the scope of the appended claims.

What I claim is:

1. In a latch of the class described, the combination of a latch housing having a recess, inner and outer knobs each having a spindle mounted to turn in said housing, a latch bolt, a bolt retractor, a roll-back connected with each knob spindle whereby upon turning either knob its roll-back acts through the retractor to retract the latch bolt, a dead-locking rod arranged axially of the knob spindles with one end projecting through an aperture in the inner knob, the projecting end forming a push button, a spring tending to move the rod in a direction to project said push button, said rod having means for holding the roll-back associated with the outer knob from axial movement with relation thereto whereby upon depressing said push button to move said rod against said spring, said roll-back associated with the outer knob is moved into said recess in the latch housing to lock the outer knob from turning movement, and means for yieldingly holding said outer roll-back and said rod in said dead-locking position.

2. In a latch of the class described, the combination of a latch housing, inner and outer knobs each having a spindle mounted to turn in said housing, a latch bolt, connections between the latch bolt and each of said spindles whereby upon turning either knob the latch bolt may be retracted, a dead-locking rod extending axially of said spindles having one end projecting through an aperture in the inner knob, a spring tending to move said rod inwardly with respect to the door, the outer knob having an aperture in alinement with said rod, and connections between said rod and said outer spindle whereby upon moving said rod outwardly with respect to the door said outer spindle is dead-locked, releasable means for holding the rod in said position against the tension of said spring, and upon moving said rod in the opposite direction said spindle is released, said rod being adapted to be thus moved outwardly by pressing on said projecting end thereof, and to be moved in the opposite direction by means of a suitable implement inserted through said aperture in the outer knob and into engagement with the adjacent end of the rod.

3. In a latch of the class described, the combination of a latch housing, inner and outer knobs each having a spindle mounted to turn in said housing, a latch bolt, a bolt retractor, a roll-back connected with each knob spindle whereby upon turning either knob its roll-back acts through the retractor to retract the latch bolt, the roll-back associated with the outer knob spindle being adapted to be shifted axially into and out of locking engagement with the latch housing, whereby when in engagement with the latch housing said outer spindle is dead-locked and when disengaged from the housing said outer spindle is released, means accessible from the inside of the door for thus shifting said outer roll-back into locking engagement with said housing, and a spring tending to shift the outer roll-back in the opposite direction, said outer roll-back and said bolt-retractor having portions adapted to engage in abutting relation when said outer roll-back is in said dead-locking position to hold said outer roll-back in said position against the tension of said spring and so arranged that upon movement of said retractor to retract the latch bolt said spring acts to release

the outer roll-back from locking engagement with said housing.

4. In a latch of the class described, the combination of a latch housing, inner and outer knobs each having a spindle mounted to turn in said housing, a latch bolt, a spring-pressed bolt retractor, a roll-back connected with each knob spindle whereby upon turning either knob its roll-back acts through the retractor to retract the latch bolt, the roll-back associated with the outer knob and the housing having portions adapted to interlock when engaged and said outer roll-back being adapted to be shifted axially into and out of locking engagement with the latch housing, whereby when in engagement with the latch housing said outer spindle is dead-locked and when disengaged from the housing said outer spindle is released, means accessible from the inner side of the door for shifting said outer roll-back into locking engagement with said housing, a spring tending to shift the outer roll-back in the opposite direction, and a projection on the retractor arranged in the path of axial movement of said outer roll-back whereby when said outer roll-back is shifted in the first-mentioned direction it depresses and rides over said projection and then said projection serves to hold said outer roll-back in locking engagement with said housing against the tension of said spring, the stop being released from the outer roll-back upon movement of the retractor to retract the latch bolt.

5. In a latch of the class described, the combination of a latch housing, inner and outer knobs each having a spindle mounted to turn in said housing, a latch-bolt, a bolt retractor, a roll-back connected with each knob spindle whereby upon turning either knob the roll-back acts through the retractor to retract the latch bolt, a dead-locking rod extending through apertures in said roll-backs having means for holding the roll-back associated with the outer knob from axial movement with relation thereto, said rod being movable longitudinally with relation to the roll-back associated with the inner knob, the outer roll-back and said latch housing having portions adapted to interlock when engaged, means for moving the locking rod axially in opposite directions to respectively position the outer roll-back in locking engagement with the latch housing to hold the outer knob and its spindle from turning movement, and to release said outer roll-back from the latch housing to permit the outer knob and its spindle to be turned, and means for holding the locking rod in the positions thus moved comprising a rounded projection on the bolt retractor arranged in the path of said outer roll-back and over which the outer roll-back is adapted to snap during said movements of the dead-locking rod in opposite directions.

6. In a latch of the class described, the combination of a latch housing, inner and outer knobs each having a spindle mounted to turn in said housing, a latch bolt, a bolt retractor, a roll-back connected with each knob spindle whereby upon turning either knob its roll-back acts through the retractor to retract the latch bolt, a dead-locking rod extending through apertures in said roll-backs, means for holding the roll-back associated with the outer knob from axial movement with relation to said rod, said rod being adapted to be moved longitudinally with relation to the roll-back associated with the inner knob, means accessible from the inner side

of the door for moving the locking-rod axially to position the outer roll-back into locking engagement with the latch housing whereby the outer knob is held from turning movement, the outer knob having an aperture in alinement with said locking-rod with its outer end spaced from the outer end of the rod to permit an implement to be inserted through said aperture into engagement with the end of the rod to move the locking-rod axially to release said outer roll-back 10 from locking engagement with the latch housing, and yielding means for releasably holding said outer roll-back in the positions thus axially moved.

7. In a latch of the class described, the combination of a latch housing, inner and outer knobs each having a spindle mounted to turn in said housing, a latch bolt, a bolt retractor, a roll-back connected with each knob spindle, whereby upon turning either knob its roll-back acts through the retractor to retract the latch bolt, a dead-locking rod extending axially of said knob spindles, means for holding the roll-back associated with the outer knob from axial movement with relation to said rod, said rod being 20 movable longitudinally with relation to the roll-back associated with the inner knob, means accessible from the inner side of the door for moving the rod axially to position the outer roll-back in locking engagement with the latch housing whereby the outer knob is held from turning movement, the outer knob having an aperture in alinement with said locking-rod with its outer end spaced from the outer end of the rod to permit an implement to be inserted through said aperture into engagement with the end of the rod to move the locking-rod axially to release said outer roll-back from locking engagement with the latch housing, and yielding means for releasably holding said outer roll-back in the positions thus axially moved.

8. In a latch of the class described, the combination of a latch housing, inner and outer knobs each having a spindle mounted to turn in said housing, a latch bolt, a bolt retractor, a roll-back connected with each knob spindle whereby upon turning either knob its roll-back acts through the retractor to retract the latch bolt, a dead-locking rod extending through apertures in said roll-backs having means for holding the roll-back associated with the outer knob from axial movement with relation thereto, said rod being movable longitudinally with relation

5 to the roll-back associated with the inner knob, means accessible from the inner side of the door for moving the locking-rod axially to position the outer roll-back in locking engagement with the latch housing whereby the outer knob and its spindle are held from turning movement, means for releasably holding the outer roll-back in said position, means acting automatically upon retraction of the latch bolt to move said rod to release said holding means and to move said outer roll-back from locking engagement with the latch housing, a lock cylinder mounted in said outer knob having a key plug in alinement with said dead-locking rod, and cooperating cams on the inner end of said key plug and the outer end of said dead-locking rod whereby when the dead-locking rod is shifted into said dead-lock position upon turning the key plug said cams act to shift the dead-locking rod in a direction to release the outer roll-back from locking engagement with the latch housing and release the outer knob.

9. A lock according to claim 8 in which said cams on the key plug and the outer end of the dead-locking rod have transverse concave and convex V-shaped cam surfaces whereby when the dead-locking rod is shifted into said dead-locking position, said surfaces are engaged and upon turning the key plug said surfaces act to shift the dead-locking rod in a direction to release the outer knob.

10. A structure according to claim 1 in which a cylinder lock is mounted in the outer knob having a key plug in alinement with the dead-locking rod, and cooperating cams are provided on the inner end of said key plug and the outer end of said dead-locking rod whereby when said rod is shifted into said dead-locking position upon turning the key plug said cams act to shift the rod in a direction to release said holding means and to move said outer roll-back out of locking engagement with the latch housing.
